INVENTOR
John Kirkby

UNITED STATES PATENT OFFICE

JOHN KIRKEBY, OF SAN LUIS OBISPO, CALIFORNIA

AUTOMATIC WATER-HEATING SYSTEM

Continuation of application Serial No. 23,589, filed April 16, 1925. This application filed July 2, 1927.
Serial No. 203,141.

My invention relates to improvements in automatic water heaters and the objects of my improvement are to provide a hot water system with a gas or electric heater which operates to heat the water as long as the tap is open, but which is automatically turned off as soon as the tap is closed. A further object is to utilize the water pressure in the pipes to shut off the supply of gas or to break the electric contacts. This application is a continuation of my application Serial Number 23,589, filed April 16, 1925.

I accomplish these objects by the means illustrated in the accompanying drawings in which—

Figure 1 is a side elevation of the parts used in my invention,

Fig. 2 is a longitudinal section of the gas valve,

Fig. 3 is a plan view of the top half of the valve,

Fig. 4 is a longitudinal section of the electric valve.

Pipe 1 draws water from the main, a stop valve 2 is to cut down the supply to a capacity less than the open faucet, for the purpose of positive operation of the valve, and may be adjusted to cut down the force as much as desired. The more nearly this valve is closed the slower the water will pass through the heater and the hotter it will run.

A check valve 3 is added to maintain pressure in the system. Pipe 4 carries water to the heater, and pipe 5 runs to the valve 6 by means of which the water pressure keeps the gas to the burner closed.

Pipe 7 connects with the gas main, and pipe 8 supplies the pilot. Since pipe 8 leads directly from the main, the pilot will burn continuously unaffected by the valve 6.

Within the valve 6 a circular diaphragm 9 consisting of one or more sheets of rubber is stretched across a cavity so that a spacious space is left between the diaphragm and the curved wall of the cavity when the diaphragm is released. The curved wall of the cavity is provided with ports 12 and 13. When the hot water faucet is closed the pressure in the system forces the diaphragm 9 against the upper wall 10 of the valve 6, and so cuts off the

flow of gas from entering chamber 11 through port 12.

When the hot water faucet is opened, however, water flows through pipe 4 and relieves the pressure in pipe 5 and in chamber 14 of the valve 6, since the valve 2 is set to a capacity less than the open faucet; the diaphragm immediately straightens allowing a free flow of gas through the ports 12 and 13 to the burner.

In order to provide a better backing for the diaphragm the ports 12 and 13 are provided with a plurality of smaller openings 15. The two halves of valve 6 are clamped together by bolts 16.

When applied to an electric heating system a pin 19 Fig. 4 runs from diaphragm 18 to a metal disk 20. Metal parts 21 are insulated from the valve Fig. 4 by gasket 22. Pressure within water system breaks the electric contact between metal disc 20 and electrodes 21, and release of pressure causes the straightening of the diaphragm 18 and makes the electric contact which sets up current in the heating element of the electric heater.

The electrodes 21 are to be wired into an electric circuit, which supplies current for an electric water heating unit. In this way Fig. 4 constitutes an automatic switch; the metal disc 20 bridging the gap between electrodes 21 when water pressure is released and the diaphragm is relaxed. Electrical water heating units are in common use and are made to fit standard pipe fittings. With an arbitrary number of electrical water heating units fitted into standard pipe fittings, allowing small water capacity, a practical electrical automatic water heating system may, in this way be constructed.

It will be understood that Fig. 4 is only an illustration of one form of my valve which may be constructed in different ways by mechanical skill. It will also be understood that thin metal or other substance may be inserted or used for diaphragm, and that the pin extending out may be used to operate a gas valve.

If water in the main should be cut off, check valve 3 would prevent the return of water from the system into the main. If the faucet

was then opened the burner would be lighted, but steam pressure within the system would soon act both against the check valve and the diaphragm cutting off the gas and extinguishing the fire.

5 I claim:

1. In an automatic water heating system the valve described, comprising a conduit adapted for connection with a water system, a diaphragm stretched over the open end thereof and a casting fit over the diaphragm and presenting a cavity facing the latter and shaped to allow the diaphragm to be pressed into intimate contact with the face thereof, the casting being formed with intake and outlet ports communicating through the cavity and adapted to be kept closed by the pressure of the water system and to relax from contact with the wall of the cavity upon release 20 of pressure, thereby opening the gas passage to the burner and a check valve and a stop cock also interposed in the system behind the said valve to regulate the flow of water.

2. In an automatic water heating system, the automatic valve described, comprising a casting having a concave face forming a cavity, intake and outlet ports communicating with said cavity through said face, a diaphragm stretched over the cavity through 30 which the gas to the burner must pass by way of the ports, means by which the pressure of the water system forces the diaphragm into intimate contact with the concave face, thereby closing both ports, means for relaxing the diaphragm from the concave face when a faucet is opened, thereby admitting gas to the burner.

3. An automatic water heating system, in which, the gas is kept closed by the water pressure and opened by release of pressure through the combined action of an open faucet ahead of the operating mechanism and a partially closed stop cock behind same, and comprising a diaphragm, two castings clamped 45 upon the rim thereof from opposite sides, so as to leave a central portion free when the diaphragm is relaxed, one of the castings having a concave face forming a cavity with intake and outlet ports communicating 50 through the face with the cavity, the said ports being connected to the gas main so that the gas can pass therethrough to the burner; the other casting being connected to the water system to allow the pressure from same to 55 bear upon one side of the diaphragm forcing it into intimate contact with the concave face of the former casting, closing both ports.

In testimony whereof I hereby affix my signature.

JOHN KIRKEBY.
